United States Patent

Des. 238,542

Patented Jan. 27, 1976

238,542

COVERED DISH

Thomas S. Shevlin, White Bear Lake, Minn., assignor to Minnesota Mining and Manufacturing Company

Filed June 17, 1974, Ser. No. 479,807

Term of patent 14 years

Int. Cl. D7—01

U.S. Cl. D7—18

FIG. 1

FIG. 2

FIG. 3

FIG. 4

FIG. 1 is a perspective view showing the top and two sides of a covered dish embodying my design;

FIG. 2 is a top view thereof;

FIG. 3 is a side elevation view thereof, all four sides having the same appearance; and

FIG. 4 is a bottom view thereof.

I claim:

The ornamental design for a covered dish, as shown and described.
